US0D1111062S

(12) **United States Design Patent** (10) Patent No.: **US D1,111,062 S**
(45) Date of Patent: ** Feb. 3, 2026

(54) **CAB INTERIOR FOR SKID STEER LOADER**

(71) Applicants: **Jiangsu Thintron Industrial Design and Research Institute Ltd.**, Suzhou (CN); **XCMG Construction Machinery Co., Ltd. Science & Technology Branch**, Suzhou (CN)

(72) Inventors: **Lanzhong Yang**, Suzhou (CN); **Xiaoyan Chen**, Suzhou (CN); **Lingling Pan**, Suzhou (CN); **Siyu Zhu**, Suzhou (CN); **Haoqi Xue**, Suzhou (CN); **Chenhe Gao**, Suzhou (CN)

(73) Assignees: **Jiangsu Thintron Industrial Design and Research Institute Ltd.**, Jiangsu (CN); **XCMG Construction Machinery Co., Ltd. Science & Technology Branch**, Jiangsu (CN)

(**) Term: **15 Years**

(21) Appl. No.: **29/991,612**

(22) Filed: **Mar. 3, 2025**

(30) **Foreign Application Priority Data**

Jan. 13, 2025 (CN) 202530018377.9

(57) **CLAIM**

The ornamental design for a cab interior for skid steer loader as shown.

DESCRIPTION

FIG. 1 is a perspective view of a cab interior for skid steer loader showing our new design;

FIG. 2 is another perspective view thereof;

FIG. 3 is another perspective view thereof;

FIG. 4 is another perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof;

FIG. 11 is a top view of the lower portion thereof; and,

FIG. 12 is a bottom view of the upper portion thereof.

1 Claim, 12 Drawing Sheets
